(57) **CLAIM**

The ornamental design for a wall-mountable structure, as shown and described.

DESCRIPTION

In a preferred embodiment, the nature of this product is a wall-mountable structure such as a portrait or landscape oriented framed mirror with inset display panel.

FIG. 1 is a right, top, front perspective view of a wall-mountable structure embodying my new design;

FIG. 2 is a front elevational view thereof;

FIG. 3 is a top plan view thereof, the bottom plan view thereof being a mirror image of the top view shown;

FIG. 4 is a right side elevational view thereof, the left side elevational view thereof being a mirror image of the right side shown;

FIG. 5 is a rear elevational view thereof;

FIG. 6 is a right, top, front perspective view of a second embodiment of my new design, the top plan and right side and rear elevational views thereof being identical to respective FIGS. 3, 4, and 5 and the front elevational view thereof being similar to FIG. 2 albeit with a reflective surface shown;

FIG. 7 is a right, top, front perspective view of a third embodiment of my new design;

FIG. 8 is a front elevational view thereof;

FIG. 9 is a top plan view thereof, the bottom plan view thereof being a mirror image of the top view shown;

FIG. 10 is a right side elevational view thereof, the left side elevational view thereof being a mirror image of the right side shown;

FIG. 11 is a rear elevational view thereof; and,

FIG. 12 is a right, top, front perspective view of a fourth embodiment of my new design, the top plan and right side and rear elevational views thereof being identical to respective FIGS. 9, 10 and 11 and the front elevational view thereof being similar to FIG. 8 albeit with a reflective surface shown.

The broken line representations in the figures are for the purpose of illustration only, and form no part of the claimed design.
